UNITED STATES PATENT OFFICE

CARL F. WALTER, OF LINCOLN, NEBRASKA

REFRIGERATOR

Application filed January 5, 1932. Serial No 584,832.

This invention has for its object the provision of a refrigerator in which the articles of food are easily accessible and any desired article may be brought to a position at the front of the refrigerator where it can be easily withdrawn without interference from other articles and without requiring a rearrangement of any of the articles in the refrigerator. The invention also has for its object the provision of a tray or holder which will firmly support and carry dishes and food and which may be turned within the refrigerator casing to bring a desired article to the front so that it may be removed. The invention is illustrated in the accompanying drawing and will be hereinafter fully described, the novel features being particularly pointed out in the appended claims.

In the drawing,

20 Figure 1 is a front elevation of a refrigerator embodying the invention,

Fig. 2 is a horizontal section on the line 2—2 of Fig. 1,

25 Fig. 3 is an enlarged detail section on the line 3—3 of Fig. 2,

Fig. 4 is an enlarged detail of the corner fastening for the tray support,

20 Figs. 5 and 6 are detail plan views showing variations.

30 The refrigerator casing or box 1 may be of any approved construction and is shown as provided with a door 2 adapted to close the entire front of the food compartment. The box is also illustrated as having a lower portion 3 in which may be mounted a compressor and its motor for mechanical automatic refrigeration. An ice compartment 4 is provided in the upper portion of the box and is shown as containing two ice drawers 5 and 40 having its bottom defined by a tray or partition 6 which may be of any approved form and removably supported in any preferred manner. Upon this tray or partition 6 are placed pans 7 to receive the water which drips from the ice drawers when they are defrosted, the pans obviously corresponding in number to the ice drawers. If the refrigerator is not adapted for automatic refrigeration but is chilled by artificial or natural blocks 45 of ice, the ice drawers may be removed and the supply of ice placed directly upon the tray 6 or rested upon the pans 7 so that the water formed by the melting ice will be collected and will not be permitted to pass down through the refrigerator and possibly spoil the food stored therein. It will be understood, of course, that the common arrangements for carrying the drip water directly to a sewer may be employed when circumstances will permit.

55 The box is preferably rectangular or square, as will be understood upon reference to Fig. 2, and in each corner of the box there is provided a bracket in the form of a stout wire or light rod 8 having one end threaded whereby it may be secured in the wall of the box and its opposite end upturned, as shown at 9, to pass through an opening provided therefor in a bar 10 whereby said bar will be supported, the extremity of the bracket being threaded to receive a wing nut 11 which may be turned home against the bar to firmly secure it in place. A nut 25 may be provided under the bar, if desired, to permit vertical adjustment when necessary to bring the bar into a level position. The bar 10 constitutes one arm or branch of a cruciform frame for supporting a tray, the several branches or bars of the frame being disposed on diagonals of the box, as shown in Fig. 2, and being connected at their centers or points of intersection by a plate 12 having a central opening therethrough. Fitted upwardly through said central opening is a screw or threaded stem 13 having a head 14 adapted to bear against the bottom of the plate and equipped with a lock nut 15, above the plate, so that when the nut is turned home, the stem will be firmly fastened in the plate. The upper extremity of this stem is reduced, as shown at 16, and has an internally threaded socket in its upper end, this reduced portion 16 being smooth throughout its outer surface. A rotatable support 17 is fitted upon the tenon or reduced extremity 16 and a tray 18 rests upon said support, as shown in Fig. 3. The tray is provided with an annular rim or flange 19 whereby dishes and plates or articles of food placed upon the tray will be 60 65 70 75 80 85 90 95 100

retained thereon and, at its center, a boss 20 is formed upon the tray. A countersunk opening is formed centrally through the boss 20 and a screw 21 is inserted through the opening to engage in the internally threaded socket of the tenon 16 so that the tray will be held to the support 17 and the stem. The screw 21 is turned home sufficiently to retain the tray in place but not so as to bind the tray against the body 17 and interfere with its free rotation as it is intended that the tray be freely rotatable in order that it may be turned to bring to the front of the refrigerator casing or box an article which may happen to be at the back of the box. Secured upon the frame 10, concentric with the stem 13, is an annular plate or ring 22 and supported in suitable brackets on this plate are rollers 23 of such diameter that they will engage against the underside of the tray 18 and thereby support the tray so that it may freely turn and will not be permitted to tilt or oscillate. As many trays and associated supports may be provided as may be desired or the capacity of the refrigerator box will admit and they may be spaced according to the desires or convenience of the owner. Inasmuch as the supporting brackets 8 are secured by being threaded into the corner walls of the refrigerator box, obviously they may be placed at such points in the height of the box as may seem most desirable. The frames carried by said brackets may be easily removed by merely releasing the wing nuts 11 and the trays may, therefore, be readily withdrawn through the front of the refrigerator box whenever cleaning of the interior of the box is necessary. The food-carrying trays are circular while the refrigerator box is rectangular and, consequently, there is ample space around the trays for circulation of air to accomplish thorough ventilation of the refrigerator and permit the cool air to reach all of the food for the preservation of the same. An article may be placed upon the tray, at the front of the same, and the tray then rotated to a greater or less degree so that the article may be moved away from the front of the refrigerator to permit additional articles to be placed upon the tray and, of course, the same operation will bring an article at the back of the refrigerator to the front when the removal of such article is desired. The provision of a plurality of supporting rollers results in maintaining the trays in a horizontal position at all times and permits them to be very easily turned to give access to any desired article. While I have illustrated the refrigerator box as having a single door and a single compartment, it will be understood that the refrigerator may be made in any desired size and may be provided with two or more tiers of food-supporting trays. It will be readily noted, upon reference to Fig.

1, that the entire space between any two trays is clear and the entire surface of each tray is available for carrying food.

When the box or refrigerator body is oblong and a space of appreciable area is left at one side of the rotary tray, an auxiliary tray 26 may be provided and supported by hooks on the walls of the box or by extensions of the bars 10, as shown in Fig. 5, and it will be understood that the inner edge of this auxiliary tray may be arcuate to fit close to the circular tray. As shown in Fig. 6, triangular trays 27 may be provided in the corners of the refrigerator box.

Having thus described the invention, I claim:

1. A refrigerator comprising a box, brackets secured in the wall of the box and consisting of hooks having upturned threaded inner ends, a frame having arms provided with terminal openings receiving the upturned ends of said brackets, nuts engaging the threaded ends of the hooks on opposite sides of the arms and bearing thereagainst to hold the frame on the brackets and permit adjustment of said frame vertically of the brackets, a food-carrying tray, and means for rotatably supporting the tray on the frame.

2. A refrigerator comprising a box, a frame mounted in and extending across the box, a stem secured in the frame at the center thereof and having a reduced upper end, a supporting body loosely mounted on said reduced upper end, a food-carrying tray resting at its middle portion upon said supporting body, and a fastening device inserted through the tray into the upper end of the stem.

In testimony whereof I affix my signature. 105
CARL F. WALTER. [L.S.]
